UNITED STATES PATENT OFFICE.

HERMANN GUTSCHMIDT, OF JERSEY CITY HEIGHTS, NEW JERSEY.

CHIMNEY-COWL.

No. 839,475.

Specification of Letters Patent.

Patented Dec. 25, 1906.

Application filed May 12, 1906. Serial No. 316,522.

To all whom it may concern:

Be it known that I, HERMANN GUTSCHMIDT, a citizen of the United States of America, and a resident of Jersey City Heights, in the county of Hudson and State of New Jersey, have invented certain new and useful Improvements in Chimney-Cowls, of which the following is a specification.

My invention relates to chimney and ventilator cowls such as are designed to prevent a reversal of draft in a chimney or ventilating-flue, due to more or less downwardly-directed atmospheric currents which might be caused, for example, by taller neighboring buildings.

My object is to produce a device of this nature that is an improvement in being at once simple in construction and entirely efficient in operation. With this end in view I have employed as principal elements a cap over and extending downward to below the top of an extension for the chimney on the outside thereof and with a space between, a hood having a small opening at the top and open at the bottom and surrounding and extending to below the cap, and a hood-shaped dividing-plate positioned between the cap and the flue, forming passages on both sides of said plate, the plate having an opening over the flue of smaller size than the flue and the lower edge of the plate being lower than the upper edge of the flue, but not so low as the lower edge of the cap.

The invention will be further explained by referring to the accompanying drawings, in which—

Figure 1 is a plan view of the device, and Fig. 2 a vertical central section, some of the lowest portion being broken away.

In the drawings, 1 is a flue portion which may be attached to and form an extension of any ventilating-flue or chimney to which the invention is to be applied. Concentrically over the flue 1 is the cap 2, which may be held in place by the brackets 3. The cap 2 has a conical portion 2^a and a cylindrical portion 2^b, and it is to be noted as of the greatest importance that the cylindrical portion 2^b extends to some distance below the top edge of the flue portion 1. Tests show that if this is not done the back pressure against the draft in the flue is increased. However, this cap alone is not sufficient for the purpose. Therefore additional parts are provided, each one of which has been found

by experiment to be essential to the best results in operation.

Inside of the cap 2 and supported in any convenient manner, as by the brackets 3^a, is a hood-shaped plate 4. The plate 4 is made up of the trunco-conical portion 4^a, and the cylindrical portion 4^b is parallel to the corresponding parts of the cap 2 and provides the passages 5 and 6, which form annular openings for the exit of the smoke or air from the flue 1. It is to be particularly noted that the lower edge of the part 4^b of the plate 4 occupies a lower horizontal plane than the top edge of the flue 1, but not so low as the lower edge of the cap 2, also that the aperture 7 at the top of the portion 4^a is of much smaller area than the flue 1. However, the space between the plate 4 and the flue 1, forming the passage 5, should throughout be equal in area to the flue 1.

Disposed outside of the cap 2 is an external hood 8, parallel to the cap 2 and forming the passage 9. The hood 8 is composed of a cylindrical portion 8^a and upper and lower truncated conical portions 8^b and 8^c, respectively, and it is to be noted as of importance that the cylindrical portion 8^a extends to below the lower edge of the part 2^b of the cap 2. The lower part 8^c forms a protector around the bottom, leaving an annular opening at 10. The hood 8 may be conveniently supported by the brackets 3. It should be noted that the truncated portion 8^b has only a very small opening 11 at the top, while the opening at 10 is large, being about equal to the passage 5 or to the flue 1, thus allowing free egress of smoke and air at this point. The part 8^c has a gentle inward slope to avoid a sharp turn at the end of the passage 9.

Normally in a chimney or ventilating-flue—that is, when there are no interfering atmospheric currents—the most of the smoke or air from the flue 1 will pass downward and out at the opening 10; but a small quantity will escape through the opening 11. A straight horizontal wind by blowing across the openings 11 at the top and 10 at the bottom has the effect, about the same as in an unprotected chimney, to somewhat increase the draft on the principle used in an atomizer. Should the wind come at a downward angle or vertically downward, the most of it will be simply turned aside, but a small amount of it will enter at the opening 11 into the upper end of the passage 9 and pass out

at the lower end thereof, carrying along with it the smoke or air coming from the passage 6 and which in turn acts likewise upon that which is emerging by the opening 5 from the flue 1. The opening 11 should be small, (about in the proportion shown,) for if it be large it has been found that downward air-currents cause too strong a draft in the flue 1. However, it should be present to give a slight assistance and to counteract the opposite effect of any eddies which might be formed in the lower part of the hood 8. It is to be noted that the downward current of air from the passage 9 does not blow across the mouth of the opening 5 nor of the passage 6, but that it is injected downward into the streams issuing therefrom, being deflected inwardly by the part 8^c, the entire mixture finally having exit at the opening 10. The principle appears to be similar to that of the injector and to produce a siphoning effect in the passage 6, which draws from the flue 1 through the aperture 7. The aperture 7 must be smaller than the flue 1 about in the proportion shown, so as to properly divide the smoke or air issuing from the flue 1, causing most of it to pass through the opening 5, but providing also additional means of escape and adequately supplying the passage 6. The device has been found less efficient without the plate 4. Should the wind strike at an upward angle, it is turned aside by the outside of the protector 8^c on the side from which the wind is coming and at the other side what enters is caught by the inside surface of 8^c and deflected upward through the passage 9, and what does not find its way out by the aperture 11 will return along the opposite side of the hood and there be of assistance instead of harmful. It is prevented from being deflected into the flue 1 by the cap 2 and the plate 4. However, irrespective of any theories as to just how or why the device of the invention has been found to be absolutely effective in full-sized operative devices in use it has also been found by experiment that none of the parts shown and described can be dispensed with. The invention of course might be modified in minor particulars without departing from the essentials thereof; but the scope of the invention is attended to in the annexed claims.

The materials to be used in construction and the manner of cutting and joining them together to form the complete device are familiar to those versed in the art and need not be detailed here.

I claim as my invention—

1. A chimney-cowl consisting of the combination of a flue for forming a continuation

to a chimney, an imperforate cap over said flue and spaced from and extending downward on the outside of said flue with its lower edge in a horizontal plane below the top of said flue, a plate spaced from the inside of said cap and from the outside of said flue and having a central opening over said flue and said plate extending downwardly below the upper edge of said flue but not so low as the lower edge of said cap, and a hood spaced outward from said cap and having a central opening at its top and open at its bottom and extending downward below the lower edge of said cap.

2. A chimney-cowl consisting of the combination of a flue for forming a continuation to a chimney, an imperforate conical cap over said flue, said cap having a lower vertical portion extending down on the outside of said flue to below the top thereof and spaced therefrom, a plate within said cap, said plate having a vertical cylindrical portion extending downward below the upper edge of said flue but not so low as the lower edge of said cap, and an upper portion extending inwardly in the form of a truncated cone, leaving an opening at the top smaller than said flue, all portions being parallel to and spaced from said cap and spaced outwardly from said flue so as to leave an area equal to said flue, a hood surrounding said cap, said hood having a middle cylindrical portion extending downward to below the lower edge of said cap, and upper and lower portions extending inwardly in the form of truncated cones, leaving an opening at the top smaller than said flue, the said middle and upper portions being parallel to and spaced from said cap, and supports for retaining said cap, plate and hood in place upon said flue.

3. In a chimney-cowl, the combination of a flue, a cap over said flue and extending to below the top thereof on the outside thereof, a hood open at the top and bottom and surrounding said cap and extending to below said cap, and a plate within said cap and extending from above to below the top of said flue.

4. In a chimney-cowl the combination of a flue having its end open, and guides forming an unbroken passage for the wind from above to below the open end of said flue on the outside thereof, and also forming unbroken passages for the flue contents from within said flue to below the open end thereof.
